US00D824022S

(12) **United States Design Patent** (10) Patent No.: **US D824,022 S**
Prentice et al. (45) Date of Patent: ** Jul. 24, 2018

(54) **FACE MASK CUSHION**

(71) Applicant: **Fisher & Paykel Healthcare Limited**,
Auckland (NZ)

(72) Inventors: **Craig Robert Prentice**, Auckland (NZ);
Bernard Tsz Lun Ip, Auckland (NZ);
Mark Arvind McLaren, Auckland (NZ);
Kyle Gregory Brown, Auckland (NZ);
Chris Onin Limpin Hipolito,
Auckland (NZ); **Mark Richard
Tomlinson**, Auckland (NZ); **Melissa
Catherine Bornholdt**, Auckland (NZ)

(73) Assignee: **FISHER & PAYKEL HEALTHCARE
LIMITED**, Auckland (NZ)

(**) Term: **15 Years**

(21) Appl. No.: **29/622,639**

(22) Filed: **Oct. 18, 2017**

Related U.S. Application Data

(62) Division of application No. 29/540,684, filed on Sep.
25, 2015, now Pat. No. Des. 800,895.

(57) **CLAIM**

The ornamental design for a face mask cushion, as shown and described.

DESCRIPTION

FIG. 1 is a top, front and left side perspective view of a face mask cushion embodying our new design;

FIG. 2 is a top, rear and left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

Broken lines are used to depict portions of the face mask cushion which form no part of the claimed design.

1 Claim, 8 Drawing Sheets
